MERCURI ALKYL PHENOL DERIVATIVES

Walter G. Christiansen, Glen Ridge, N. J., assignor to E. R. Squibb & Sons, New York, N. Y., a corporation of New York

No Drawing. Original application September 13, 1934, Serial No. 743,840. Divided and this application August 30, 1938, Serial No. 227,503

5 Claims. (Cl. 260—433)

This invention relates to, and has for its object the provision of, certain mercuri alkyl phenol derivatives.

This case is a division of application Serial No. 5 743,840, filed September 13, 1934, now Patent No. 2,137,236.

The compounds of this invention are mercuri alkyl phenol derivatives of the group consisting of

wherein one R represents a member of the group consisting of halogen and nitro, and the other represents a straight-chain alkyl having at least 20 three carbon atoms. They may be prepared by interacting the corresponding unmercurated alkyl phenol derivatives with mercuric acetate, and replacing the acetoxy with the desired anion 25 by means of the compound of that anion with an alkali metal (cf. Whitmore's Organic Compounds of Mercury, 1921, pp. 257, 258). These mercuri alkyl phenol derivatives have been found to be active germicides.

30 The following examples are illustrative of the invention:

EXAMPLE 1

Acetoxymercuri 2-chloro 4-propyl phenol

45 4.71 g. 2-chloro 4-propyl phenol is dissolved in 25 cc. methyl alcohol, and while the solution is refluxed on a steam-bath, 8.7 g. mercuri acetate dissolved in 25 cc. water slightly acidulated with acetic acid is added rapid-dropwise with mechanical stirring. After three hours of refluxing, a 50 test for divalent mercury being negative, the re-

action mixture is filtered, washed, and dried as in the foregoing examples, yielding the desired compound in the form of white crystals.

EXAMPLE 2

Hydroxymercuri 2-nitro 4-propyl phenol

2.3 g. 2-nitro 4-propyl phenol is dissolved in 25 cc. methyl alcohol, and while the solution is refluxed on a steam-bath, a solution of 4 g. mercuric acetate in 12 cc. water slightly acidulated with acetic acid is added. After four hours of refluxing, a test for divalent mercury being negative, the crystalline orange precipitate, the desired compound, is isolated as in the preceding example. Purification may be effected by dissolving (to an orange solution) in dilute alkali, filtering out the slight residue, and precipitating with dilute acetic acid.

Among the numerous other compounds that may be prepared in accordance with the invention are the following (the chloro, the cyano, the thiocyanato, the nitro, and the hydroxy compounds being formed by treating solutions of the acetoxy compound with, respectively, the chloride, and cyanide, the thiocyanide, the nitrate, and the hydroxide, of an alkali metal).

Anhydromercuri 2-chloro 4-normal-butyl phenol.

Anhydromercuri 2-chloro 4-normal-amyl phenol.

Chloromercuri 2-chloro 4-propyl phenol.

Acetoxy mercuri 2-bromo 4-propyl phenol.

Nitratomercuri 2-nitro 4-normal-butyl phenol.

Thiocyanamercuri 2-nitro 4-normal-amyl phenol.

Chloromercu 2-nitro 4-propyl phenol.

Acetoxymercuri 2-propyl 4-chloro phenol.

Hydroxymercuri 2-propyl 4-nitro phenol.

The invention may be variously otherwise embodied within the scope of the appended claims.

I claim:

1. Mercuri alkyl phenol derivatives of the group consisting of

5

10

wherein one R represents a member of the group consisting of halogen and nitro, and the other represents a straight-chain lower alkyl having at least three carbon atoms.

15

2. Mercuri alkyl phenol derivatives of the group consisting of

5

10

wherein R represents a straight-chain lower alkyl having at least three carbon atoms.

3. Hydroxymercuri-2-nitro 4-propyl phenol.
4. Anhydromercuri 2-chloro 4-normal - amyl phenol.

5. Acetoxymercuri 2-propyl 4-chloro phenol.

WALTER G. CHRISTIANSEN.
